Attorneys*

UNITED STATES PATENT OFFICE.

HOWARD M. DUDLEY, OF PHILADELPHIA, PENNSYLVANIA.

APPARATUS FOR DYEING, SCOURING, OR OTHERWISE TREATING YARN OR OTHER FIBERS IN THE HANK OR SKEIN.

Application filed August 7, 1922. Serial No. 580,303.

To all whom it may concern:

Be it known that I, HOWARD M. DUDLEY, a citizen of the United States, and a resident of Philadelphia, Pennsylvania, have invented certain new and useful Improvements in Apparatus for Dyeing, Scouring, or Otherwise Treating Yarn or Other Fibers in the Hank or Skein, of which the following is a specification:

10 My present invention relates more particularly to that type of yarn dyeing or treating machines in which the hanks or skeins of yarn or other fibers, are carried by reels, which reels are arranged to be rotated in a body of liquid disposed within a tank or vat, and in which provision is made for imparting independent movement to the individual hanks or skeins of yarn as the reel is rotated.

20 One object of my present invention is to provide a structure of this type with simple and efficient means, hydraulically operated, whereby the reel, together with the hanks or skeins of yarn supported thereby, may be lifted within the vat or tank.

A further object of my invention is the provision of means whereby the reel may be rotated, in either direction during the lifting operation.

30 A further object of my invention is to provide means for carrying a deeper body of liquor within the vat or tank whereby the extent of submergence of the respective hanks or skeins is materially increased.

35 A further object of my invention is to provide means for equalizing the hydraulic or other fluid-pressure employed for elevating the reel; suitable cylinders being provided, with pistons therein actuated by hydraulic or other fluid-pressure.

40 A further object of my invention is to provide guiding means that will insure uniform movement of the reel during the up and down movements of the same within the tank or vat.

45 And a still further object of my invention is to provide means for protecting the means for effecting rotation of the reel from contact with the dyeing or treating liquor.

50 These and other features of my invention are more fully described hereinafter; refer-

ence being had to the accompanying drawings, in which:

Figure 1, is a sectional elevation of one form of vat or tank containing a reel for supporting the skeins or hanks of yarn to be dyed or otherwise treated, together with the mechanism for raising and lowering the reel and for rotating the same.

Fig. 2, is a sectional view on the line II—II, Fig. 1.

Fig. 3, is a sectional view on the line III—III, Fig. 1.

Fig. 4, is a view similar to Fig. 1, of another form of structure within the scope of my invention, and

Fig. 5, is a sectional plan view on the line V—V, Fig. 1, illustrating a detail of construction within the scope of my invention.

In the drawings, I have illustrated a suitable form of tank or vat 1, which may comprise side walls 2, end walls 3, a bottom 4 which is preferably semi-circular, and a cover 5. The side walls 2 are preferably provided with openings 6, normally closed by covers or doors 7, hinged at 8, and having suitable packing 9 disposed at their marginal edges to insure a liquid-tight joint; such covers or doors being secured in place by clamping members 10.

Within the vat or tank, a reel for receiving the hanks or skeins of yarn or other fibers, indicated at X, is disposed, which reel may comprise end spiders 11 and 12, and a central spider 13, which may be connected to and spaced from the end spiders 11 and 12, by a series of tie bars 14; the several spiders being suitably mounted upon and secured to a shaft 15, which may be raised and lowered, and rotated, with the reel, as hereinafter described.

Between the respective spiders, suitable supporting sticks 16 and 17 for the hanks or skeins of yarn or other fiber are placed; the sticks 16 being polygonal and rotatable in the spiders in the usual and well known manner, for the purpose of imparting movement to the skeins or hanks of yarn or other fiber to avoid the danger of stick marks. For this purpose, the outer ends of the sticks 16, may be provided with star-wheels 16^a, adapted to engage suitably disposed

projections mounted in the vat or tank, when the reel is rotated.

The end walls 3, of the vat or tank are provided with recessed portions 20, to accommodate bearing blocks 21 and 22, receiving the ends of the shaft 15, and said bearing blocks may be carried by collars 23, supported by rods 24, hung from a beam 25, disposed above the vat or tank; the 10 cover 5 of the latter being apertured at 26 for the passage of said rods.

For the purpose of rotating the reel within the vat or tank, the bearing block 21, receiving one end of the shaft 15, may be 15 extended to provide a recessed portion 28, in which a sprocket-wheel 29, may be disposed, which sprocket-wheel may be driven by a chain 30, driven by a sprocket-wheel 31, on the end of an armature shaft 32, of 20 a motor 33, mounted on the beam 25. This chain is preferably enclosed by a casing 34, sealed to the bearing block 21, over the recess 28 receiving the sprocket-wheel 29.

In structures of this kind, it is desirable 25 to elevate the reel for the purpose of placing or examining the skeins or hanks of yarn or other fibers carried thereby, and for this purpose I employ means normally supporting the beam 25, which means are designed to raise and lower said beam and with it the reel suspended therefrom.

Disposed adjacent the vat or tank, in the present instance being shown as supported by its end walls 3, are a pair of cylinders 35 and 36, having pistons 35^a and 36^a, respectively; the upper ends of which pistons are connected at 35^b and 36^b, to the beam 25. To raise the pistons in said cylinders and with them the beam and the reel suspended therefrom, pressure may be admitted 40 to said cylinders via pipes 38 and 39, from a suitable supply pipe 40. This pressure may be controlled by a suitable three-way valve 41, whereby said supply pipe may be 45 open to pressure or exhaust, as may be desired, to raise or lower the reel. The collars receiving the bearing blocks 21 and 22 move up and down in the recessed portions of the side walls 3, and these collars are 50 preferably grooved at the sides, as indicated at 23^a, for sliding engagement with ribs 20^a, formed on the walls of said recessed portions 20, as shown in Figs. 3 and 5.

In order that the pistons 35^a and 36^a may 55 move with the desired precision; maintaining the beam and the reel shaft suspended therefrom in proper horizontal position, I may provide the cylinders 35 and 36 with piped connections 38^a and 39^a, adjacent to their upper ends, through which pressure 60 may enter and exhaust alternately with the inlet and exhaust of pressure through the pipes 38 and 39, in the raising and lowering of said pistons.

65 To counterbalance the motor 33, the beam

25, may be provided with a weight 45 at the end opposite said motor. Current to actuate the motor may be supplied by means of a flexible conductor 46, and for the purpose of controlling the application of current to 70 said motor, I may employ a controller, such as indicated at 47.

The form of structure illustrated in Fig. 4, is substantially the same as that shown in Figs. 1, 2, 3, excepting that it is shaft driven. 75 In Fig. 4, the bearing block 21^a is of substantially the same character as that illustrated at 21, in Fig. 1, but the shaft 15^a carries a bevel pinion 48, adapted to mesh with a bevel pinion 49, carried at the end 80 of a vertical shaft 50, which may receive its motion in any suitable manner from the armature shaft 32^a of a motor 33^a, carried by a beam 25^a.

The shaft 50 may be enclosed by a casing 34^a in a manner substantially similar to the encasement of the sprocket chain; such casing 34^a being sealed in any suitable fluid-tight manner to the bearing block 21^a. In all other respects, the construction and operation of the structure shown in Fig. 4, may be identical with that of the structure shown in Figs. 1, 2 and 3. It may be noted further that whereas in the structure shown in Figs. 1, 2 and 3, the cylinders are supported 90 by the end walls of the vat or tank, in the structure shown in Fig. 4, the cylinders are supported by suitable stands 51, from the floor or base upon which the vat or tank rests. 95

If desired, the enclosing casings 34 and 34^a may extend the full height of the vat or tank and pass with the chain or shaft through the opening provided for the latter in the top or cover of the vat or tank when 100 the reel is lifted.

It will be understood, therefore, that when the motor is in action, the reel will be rotated within the bath of liquid contained within the vat or tank which, by reason of the closed sides of the latter, is much deeper than ordinarily provided, and that when pressure is admitted to the lower portion of the cylinder, the reel may be gradually raised. The vertical movement of the reel 110 may be simultaneous with or independent of the rotation of the reel.

I claim:

1. The combination, in apparatus for dyeing or treating yarn and other fibers in the hank or skein, of a closed tank, a reel rotatably mounted therein, a shaft carrying said reel, bearings in which said shaft is rotatably mounted arranged for vertical movement with respect to the side walls of 120 said tank, and direct hoisting means disposed above the tank and outside the latter and connected to said bearings for raising and lowering the reel.

2. The combination, in apparatus for dye- 125

ing or treating yarn and other fibers in the hank or skein, of an enclosed tank, a reel rotatably mounted therein, a shaft carrying said reel, enclosed bearings in which said shaft is rotatably mounted arranged for vertical movement in the side walls of said tank, means disposed above the tank and outside the latter and connected to said bearings for raising and lowering the reel; 10 the side walls of the tank being recessed to accommodate said bearings, and means for rotating the reel when disposed at any height within the tank.

3. The combination, in apparatus for 15 treating or dyeing yarn and other fibers in the hank or skein, of a closed tank, a reel rotatably mounted in said tank, a shaft carrying said reel and disposed wholly within the tank, enclosed bearings in which the 20 ends of said shaft are rotatably mounted arranged for vertical movement with respect to the sides of said tank, and vertically movable hoisting means disposed above the tank and connected to said bearings for effecting 25 vertical movement of the reel within the tank.

4. The combination, in apparatus for 30 treating or dyeing yarn and other fibers in the hank or skein, of a tank closed on all sides, a reel rotatably mounted in said tank, a shaft carrying said reel, bearings in which said shaft is rotatably mounted arranged for vertical movement with respect to the sides of said tank, vertically movable hoisting means disposed above the tank and connected to said bearings for effecting vertical 35 movement of the reel within the tank; the side walls of the latter being vertically recessed to accommodate said bearings, and means carried by the vertically movable hoisting means for rotating the reel when disposed at any height within the tank.

5. The combination, in apparatus for 45 treating or dyeing yarn or other fibers in the skein or hank, of a vat or tank, a reel rotatably mounted in said vat or tank, a shaft carrying said reel, bearings in which said shaft is rotatably mounted, a beam extending across the vat or tank, rods depending therefrom and connected to said bearings, means for raising said beam to impart vertical movement to said bearings; the side walls of the structure being recessed to accommodate said bearings, a motor carried by said beam, and means whereby said motor may effect rotation of the reel.

6. The combination, in apparatus for 50 treating or dyeing yarn or other fibers in the skein or hank, of a vat or tank, a reel rotatably mounted therein, a shaft carrying said reel, bearings in which said shaft is rotatably mounted, a beam extending across the vat or tank, rods depending therefrom and connected to said bearings, fluid-pressure means for raising said beam to impart

vertical movement to said bearings; the side walls of the structure being recessed to accommodate said bearings, a motor carried by said beam, and means whereby said motor may effect rotation of the reel. 70

7. The combination, in apparatus for 75 treating or dyeing yarn and other fibers in the hank or skein, or a tank, a reel rotatably mounted therein, a shaft carrying said reel, bearings in which said shaft is rotatably mounted arranged for sliding movement with respect to the side walls of the tank, a beam disposed above the upper part of the tank from which said bearings are suspended, and means for effecting vertical 80 movement of said beam.

8. The combination, in apparatus for 85 treating or dyeing yarn and other fibers in the hank or skein, of a tank, a reel rotatably mounted therein, a shaft carrying said reel, bearings in which said shaft is rotatably mounted arranged for sliding movement with respect to the side walls of the tank, a beam disposed above the upper part of the tank from which said bearings are suspended, and fluid actuated means at the sides of 90 the tank for effecting vertical movement of said beam.

9. The combination, in apparatus for 95 treating or dyeing yarn and other fibers in the hank or skein, of a tank, a reel rotatably mounted therein, a shaft carrying said reel, bearings in which said shaft is rotatably mounted arranged for sliding movement with respect to the side walls of the tank, a beam disposed above the upper part of the tank from which said bearings are suspended, means for effecting vertical movement of 100 said beam, and means for rotating said reel including an electric motor carried by the 105 beam and vertically movable therewith.

10. In a structure such as set forth in 110 claim 5, motion transmitting means driven by the motor and operatively connected to the reel for rotating the latter.

11. In a structure such as set forth in 115 claim 5, motion transmitting means driven by the motor and operatively connected to the reel for rotating the latter, and a casing carried by one of the shaft bearings for enclosing said motion transmitting means to prevent access of the dye liquor thereto.

12. In a structure such as set forth in 120 claim 5, a sprocket-chain driven by the motor; said sprocket-chain passing over a sprocket-wheel carried by the reel shaft for rotating the reel.

13. In a structure such as set forth in 125 claim 5, a sprocket-chain driven by the motor; said sprocket-chain passing over a sprocket-wheel carried by the reel shaft for rotating the reel, and a casing carried by one of the shaft bearings for enclosing said sprocket-chain to prevent access of the dye liquor thereto. 130

14. In apparatus of the character described, the combination of a dye vat closed on all sides and having recessed end walls, a reel, a shaft for said reel disposed wholly within the tank, bearings in which said shaft may rotate adapted to said recessed portions of the end walls; the side wall of said dye tank being apertured, a door closing said aperture, and a fluid-tight joint for the marginal edge of said door. In witness whereof I have signed this specification.

10
HOWARD M. DUDLEY.
